CONTROLLING APPARATUS FOR REFRIGERATING SYSTEMS

John Kirgan, Easton, Pa., and John A. MacLean and George H. Woodard, Phillipsburg, N. J., assignors to Ingersoll-Rand Company, Jersey City, N. J., a corporation of New Jersey

Application October 24, 1936, Serial No. 107,356

17 Claims.

This invention relates to controlling apparatus, and particularly to controlling apparatus for refrigerating systems. An object of the invention is to protect a refrigerating system by automatically stopping the operation thereof and the production of refrigeration therein when parts of the system function improperly and further operation of the system may result in damage thereto. A further object of the invention is to provide in a refrigerating system having a suitable power unit coupled to operate an evacuator for removing vapor from the evaporator of the system, means dependent upon a device driven at a speed corresponding to that of said unit for actuating and circulating a pressure agent, through which the operation of said unit can be suspended whenever its speed rises above a predetermined value, said device having in combination therewith connections by which the starting of said unit and of the refrigerating system is facilitated.

Another object of the invention is to provide a refrigerating system having an evaporator in which a refrigerating medium is cooled, a pump to deliver the refrigerant from the evaporator, an evacuator for the evaporator and a power unit for operating the evacuator, with means for cutting off the power medium supplied to said unit whenever the pump for removing the cooled refrigerant from the evaporator stops or fails to properly discharge said refrigerant, or whenever the refrigerant in said evaporator threatens to inflict damage upon other parts of the system.

With the foregoing and other objects and advantages in view the nature of the invention will be made clear in the following description which, taken with the drawings, discloses one or more embodiments of the invention. We of course reserve the right to make changes which do not depart from the principle of the invention or exceed the scope and spirit of the appended claims.

In the drawings Figure 1 shows an outline partly in section of a refrigerating system with controlling apparatus according to our invention, and

Figure 2 is a more or less diagrammatic view, partly in section of a modified construction of the controlling apparatus.

On the drawings the same numerals identify the same parts throughout.

Referring first to Figure 1 we show at 1 a closed receptacle called an evaporator to which a liquid refrigerant in finely divided form is supplied through an inlet header 2 having a number

of jet openings through which the refrigerant issues in the form of a spray. Some of the liquid is vaporized in the evaporator 1 and this vapor is withdrawn through an opening 3 which is connected to an evacuator 65 such as a centrifugal compressor of the conventional design, as is illustrated in Fig. 2. This compressor may be driven by a unit such as a steam turbine enclosed in a housing 4. The compressor connected to the vapor outlet 3 not only removes vapor but maintains a very high vacuum in the evaporator 1, thus insuring a continuous vaporization of part of the refrigerant. The bulk of the refrigerant remains liquid and is cooled in the evaporator 1 by the formation of vapor therein, the cooled liquid being withdrawn through a discharge conduit 5 connected to the bottom of the evaporator. The conduit 5 leads to the space 6 which may be an air cooler or any other device wherein the refrigerant absorbs heat. It is afterwards returned at a higher temperature to the header 2 and is cooled again for further use.

The turbine for driving the evacuator is supplied with a power medium, such as steam, through a pipe or conduit 7 in which there is a controlling valve 8. This valve is manually opened to initiate operation of the turbine and the system. However, as soon as the system is in operation this valve 8 is hydraulically controlled and is thus automatically opened or closed in accordance with the operating conditions of the system. For this purpose we provide a reservoir 9 from which oil or other pressure agent is withdrawn by a pump 10a and forced through a pipe 11 to a casing 12 containing a piston 13. Attached to this piston is a rod 14 that projects to the outside of the casing 12 and is connected to the valve means 8. The device indicated at 10a runs at a speed corresponding to the speed of the evacuator since both the evacuator 65 and the pump 10a are connected to the turbine shaft 66 (see Fig. 2). As long as proper conditions exist the pressure of the oil or the other liquid withdrawn from the reservoir 9 will be exerted on the piston 13 to keep the valve 8 open so that the operation of the refrigerating system can be continued.

Within the casing 12 is a spring 15 which tends to close the valve 8, and to cause this valve to remain open, the oil drawn from the reservoir 9 by the pump 10a is forced into the top of the casing 12 through a pipe 16 at a pressure which overcomes the spring 15 and forces the piston 13 outward. The apparatus for controlling the valve 8 so that it remains open but closes when re-

quired, comprises not only the pump 10a and the casing 12 of the piston 13, but a system of additional parts and members to facilitate opening the valve 8 at starting, to prevent the normal speed of the turbine from being exceeded and to bring about the closing of the valve if for any reason the flow of the cooled refrigerant to the coil 6 is stopped or the cooled refrigerant rises to a level that is too high in the evaporator 1 and threatens to enter the outlet 3 so as to damage the evacuator.

To this end the casing 17 of the valve 8 has a projection which affords means for pivotally mounting thereon a lever 18. This lever is supported intermediate its ends, one of which is pinned to the rod 14 and the other end to one extremity of the lever 19 by a suitable connection 20. The opposite end of the lever 19 is pinned at 21 to another lever 22 mounted between its ends on a fixed fulcrum 23. Adjacent the pin 21 the lever 19 has a pin-and-slot connection with a rod 24 of a piston valve 25 in the casing 26. This piston valve has a recess 27 extending around it adjacent the end which is nearer to the rod 24 and adjacent the other or inner end has a similar circumferential recess 28. The lever 19 has a handle 29 adjacent the connection 20 so that it can be manipulated to start the system.

We also connect another pump device 10b to be driven by the turbine 4 and to withdraw liquid from the reservoir 9 and force it through a pipe 30 into a casing 31 containing a piston 32. The piston 32 is joined by a rod 33 to the end of the lever 22 remote from the pin 21 and the effect is such that when the piston 32 is moved outward or downward with respect to the casing 31 the lever 22 is so actuated that it tends to move the connected end of the lever 19 upward. In the casing 31 a spring 34 opposes the movement of the piston 32 under the action of the pressure of the liquid admitted through the pipe 30.

With these connections the turbine in the housing 4 can be easily started and prevented from exceeding a given speed. When the turbine is not running the pumps 10a and 10b will be motionless and the spring 15 will act upon the means comprising the piston 13 and valve 8 so as to hold the valve 8 shut. Also the spring 34 will move the piston 32 to the top of its range and the lever member 19 will therefore be held by the lever members 18 and 22 in its lowest position. To start, the operator must pull the handle 29 of the lever 19 upward. The lever 19 then swings a little about the pin 21, moving the valve 24 outward somewhat but not enough to cut off the pipe 11 from the pipe 16. The valve 8 is thus opened slightly so that steam flows into the housing of the turbine 4 and starts the latter, and the pumps 10a and 10b are also set into operation. Oil then flows through the connections 11 and 16 entering the casing 12 and forcing the piston 13 outward to open the valve further. Thus the turbine soon reaches the full operating speed. Any oil that is below the piston 13 as it moves downward is forced out through a pipe or connection 35 which now communicates with a pipe or connection 36 through the recess 27 in the valve 24 and is returned to the reservoir 9.

With the turbine now running the pump 10b forces oil into the casing 31, moves the piston 32 downward and lifts the end of the lever 22 connected to the lever 19. This movement may result in causing the valve 24 to close the ports in the casing 25 leading to the pipes 16 and 35. The oil in the top of the casing 12, however, will

continue to hold the valve 8 fully open, and the turbine continues to run at the fixed speed desired. If, however, the selected maximum speed of the turbine is exceeded the piston or element 32 will be moved outward, since the turbine is directly connected to the pump 10b an increase in speed of the turbine will increase the speed of the pump and the pressure of the fluid supplied thereby, far enough to lift the end of the lever 19 connected to the valve rod 24 and move this valve so as to put the pipe 35 in connection with the pipe 11. Pressure fluid will now enter the casing 12 below the piston 13, lift this piston and shut the valve 8. The same movement of the valve 24 connects the pipe 16 around the inner end of this valve with the pipe 37 which delivers to the pipe 36 and the oil above the piston 13 is thus returned to the reservoir 9.

The top of the casing 31 is joined by a pipe or connection 38 to the reservoir 9 and this pipe contains a hand adjustable valve 39. By this valve, the pressure with which the piston 32 will act to make the valve 8 close, can be regulated. Thus the maximum speed of the turbine and the evacuator can be determined.

The pipe 11 is also connected to the reservoir 9 by a return pipe 40. This pipe is normally kept closed by a valve 41, but which may open and bring about closing of the valve 8 when some danger arises in the system outside of the turbine 4 and which makes further operation inadvisable. The valve 41 for the release connection or pipe 40 is mounted in a casing comprising an extension 42 which surrounds the stem 43 of the valve 41. This stem is encircled by a spring 44 engaging a head 45 on the valve stem and pushing against this head so as to tend to open the valve 41. A diaphragm 46 engages the head 45 and over this diaphragm is a cover 47 connected by a pipe 48 to any suitable source of pressure which for the sake of convenience is here shown as the refrigerant pipe 5 leading to the space 6. In this pipe adjacent the evaporator is a force pump or the like means 49 operated by the motor 58 and the length of the pipe 5 leading to the space 6 has a non-return-check valve 50 therein. The connection 48 is united to the pipe 5 between pump 49 adjacent the evacuator and the one-way valve 50. Hence so long as the pump 49 is working and forces refrigerant to the space 6 the pressure of this refrigerant in the pipe 48 forces the diaphragm 46 against the head 45 and keeps the valve 41 closed. With these connections, if the pressure falls in the pipe 48, the valve 41 opens, and the pressure above the piston 12 is immediately reduced because the discharge of the pump 10a is now directed back into the reservoir 9 through the open pipe 40, and the pressure agent is thus rendered ineffective to hold the valve 8 open. Thus if for any reason refrigerant stops flowing under pressure in the pipe 5 the turbine is shut down and the production of further refrigeration effect is impossible until the defect has been remedied. This arrangement also renders it impossible for the turbine to operate automatically until after the pump 49 has been started and the refrigerant put in circulation.

Hence in practice the refrigerant will be cooled in the evaporator 1 and transmitted to the space 6, and as long as the refrigerant is forced under pressure through the pipe 5 the valve 41 will be shut. If the maximum speed of the turbine and evacuator is exceeded the pressure fluid in the casing 31 moves the valve 24 up-

ward and the oil circulated by the pump 10a enters the casing 12 through pipe 35, under the piston 13 to lift this piston and close the valve 8, and the oil above the piston 13 is exhausted through the pipes 16 and 37 and flows back into the reservoir 9. If for any reason the pump 49 should stop, so that the liquid in the pipe 48 is no longer under pressure, the release valve 41 will open. Fluid circulated by the pump 10a 10 will then be returned from the pipe 11 and from the pipe 16 from the top of the casing 12 through the pipe or release connection 40 back into the reservoir 9 regardless of the speed of the turbine, and the fluid in the casing 12 will no longer 15 be under sufficient pressure to hold the piston 13 down. Under these conditions the spring 15 will close the valve 8 and stop the turbine and the evacuator.

Whenever the pump stops the pressure of the 20 liquid in the pipe 48 will drop to such an extent as to allow the valve 41 to open, and bring about a complete shut down of the system. The result would be as before to short circuit the pump 10a and allow the valve 8 to shut.

25 Figure 2 shows a modification in which the pipe 48 has a regulating valve 60 therein similar to the valve 39. A branch pipe 61 from the pipe 48 leads into the evaporator 1 to a casing 62 containing a rotary valve 63. This casing 30 also has a drain pipe connection 64 leading to the sewer. The rotary valve 63 is connected to the float lever 51. In normal operation the pressure of the cooled refrigerant in the pipe 48 will hold the valve 41 in the casing 42 closed as 35 before. If the means for discharging the refrigerant, such as the pump 49, stops this valve will open and if the refrigerant becomes too deep in the evaporator 1 the float lever 51 will be lifted to move the valve 63 so as to open communication between the pipe 61 and 64. The 40 pressure in the pipe 48 will thus drop to permit the valve 41 to open with the same effect as before whereby the pump 10a will circulate oil from the reservoir 9 and back into the reservoir 45 immediately through the pipe 40 so that the piston 13 will be free to move upward and close the valve 8.

From the foregoing description it will be clear that the controlling apparatus will operate effectively for the intended purpose. The connections are very easy to make and the parts are simple in operation and certain to function as required.

We claim:

1. In a refrigerating system comprising an evaporator and a variable speed unit to remove vapor from the evaporator, fluid pressure operated means to control operation of said unit, means to supply fluid under pressure to said fluid pressure operated means operated by said variable speed unit and varying the pressure in accordance with variations in the speed of the unit, and independent pressure responsive means normally rendering the last said means operative.
2. In a refrigerating system comprising an evaporator and a variable speed unit to remove vapor from the evaporator, means to supply power medium to the unit, fluid pressure operated means to control the first means, means to supply fluid under pressure to said fluid pressure operated means operated by said variable speed unit and varying the pressure in accordance with variations in the speed of the unit, and independent pressure responsive means normally rendering the last said means operative.

3. In a refrigerating system comprising an evaporator having inlet and discharge means for liquid, and a variable speed unit to cause removal of vapor from the evaporator, means to transmit a power medium to the unit, a device 5 for placing an operating fluid under pressure operated by said variable speed unit and changing the pressure in accordance with variations in the speed of the unit, means operated by changes in the pressure of the fluid to control 10 the transmission of said medium, and means acting in response to a decrease in the pressure of the liquid discharged from the evaporator to relieve said pressure fluid to cause the last said means to suspend the transmission of power 15 medium.

4. In a refrigerating system comprising an evaporator having inlet and discharge means for liquid, and a variable speed unit to cause removal of vapor from the evaporator, means to 20 transmit a power medium to the unit, a device for placing an operating fluid under pressure operated by said variable speed unit and changing the pressure in accordance with variations in the speed of the unit, means operated by changes 25 in the pressure of the fluid to control the transmission of said medium, and means controlled by liquid discharging from the evaporator and acting responsively to a falling pressure of such liquid to relieve the pressure fluid to cause the 30 last said means to suspend the transmission of power medium.

5. In a refrigerating system comprising an evaporator adapted to discharge refrigerant, and a variable speed unit to remove vapor from the 35 evaporator, means to supply power medium to the unit, a device to place an operating fluid under pressure operated by said variable speed unit and changing the pressure in accordance with variations in the speed of the unit, fluid 40 pressure means actuated by said fluid under pressure associated with the supply means to regulate the supply of power medium to the unit, means to render the fluid under pressure ineffective to actuate said fluid pressure means, and pressure operated means normally maintaining 45 the last said means inoperative.

6. In a refrigerating system comprising an evaporator adapted to discharge refrigerant, and a variable speed unit to remove vapor from the 50 evaporator, means to supply power medium to the unit, a valve associated with said means, a device to place an operating fluid under pressure operated by said variable speed unit and changing the pressure in accordance with variations in the speed of the unit, a fluid pressure 55 means actuated by said fluid under pressure to open and close the valve in accordance with variations in the pressure of the fluid, means to render the fluid under pressure ineffective to 60 actuate said fluid pressure means and to permit said valve to close, a pressure actuated valve in the last said means, and independent means to supply fluid under pressure to said pressure actuated valve to maintain it open.

7. In a refrigerating system, an evaporator, a supply conduit for a medium to furnish power for the removal of vapor from said evaporator, means for discharging refrigerant from the evaporator, means to maintain the flow of medium 70 through the conduit dependent upon the pressure of the refrigerant discharged from the evaporator, and means responsive to a certain level of the refrigerant in the evaporator to reduce the pressure of the discharged refrigerant and 75

thereby cause suspension of the flow of said medium.

8. The combination of an evaporator having a pump to discharge refrigerant therefrom, a conduit to supply power medium to be expended in the removal of vapor from the evaporator, a device to place a fluid under pressure, members acted on by the pressure fluid to control the flow of power medium through said conduit, release means for the fluid, a valve in said last means normally held in closed position by the pressure of discharge refrigerant, a float in the evaporator, and means actuated by the float to render the pressure of the refrigerant ineffective to thereby open said valve and cause said release means to cut off the supply of power medium.

9. In a refrigerating system, an evaporator, means to supply a power medium to be expended in removing vapor from the evaporator, a conduit and pump to discharge refrigerant from the evaporator, a device to place a fluid under pressure, means actuated by the pressure fluid to control the flow of said power medium, a release pipe for the pressure fluid, a fluid pressure responsive valve in said pipe, a pipe connection from said conduit to said valve, a drain pipe for said connection, and a valve and float in the evaporator to control operation of said drain pipe.

10. In a refrigerating system, an evaporator having inlet means for liquid, a pump for removing liquid from the evaporator, an evacuator for removing vapor from the evaporator, pressure-responsive means including a member acted on by liquid discharged by the pump to control the operation of the evacuator, and means responsive to a certain level of the liquid in the evaporator to effect a decrease in the pressure of the liquid acting on said member to cause the member to stop the operation of the evacuator.

11. In a refrigerating system, an evaporator having inlet means for liquid, a pump for removing liquid from the evaporator, an evacuator for removing vapor from the evaporator, pressure-responsive means including a member acted on by liquid discharged by the pump and acting responsively to a falling pressure of such liquid to stop the operation of the evacuator, and means responsive to a certain level of the liquid in the evaporator to relieve the pressure of the liquid acting on said member.

12. In a refrigerating system, an evaporator having inlet and discharge means for liquid, a rotary evacuator for removing vapor from the evaporator, a fluid actuated motor for driving the evacuator, a conduit for supplying power fluid to the motor, pressure-actuated governor means comprising a pressure-responsive valve in the conduit and a pump driven by the motor and evacuator for supplying pressure fluid for actuating the valve, a release connection for the pressure fluid, a pressure-responsive valve in the connection normally held closed by the pressure of the liquid discharging from the evaporator, and means for effecting a reduction in the pressure of the liquid acting on the last said valve to open the valve, relieve the pressure fluid and cause the first said valve to cut off the flow of power fluid to the motor.

13. In a refrigerating system comprising an evaporator and a variable speed unit to remove vapor from the evaporator, means to supply a power medium to the unit, valve means to control the supply means, fluid pressure operated means to control the valve means, and means to supply fluid under pressure to the fluid pressure operated means operated by said variable speed unit and varying the pressure in accordance with variations in the speed of the unit, and separate fluid actuated means to control operation of the last said means.

14. In a refrigerating system comprising an evaporator and a variable speed unit to remove vapor from the evaporator, means to supply power medium to the unit, valve means to control the supply means, manual means to regulate the valve means, fluid pressure operated means to control the valve means, means to supply fluid under pressure to the fluid operated means operated by said variable speed unit and varying the pressure in accordance with variations in the speed of the unit, and fluid actuated means to control operation of the last said means.

15. In a refrigerating system comprising an evaporator and a variable speed unit to remove vapor from the evaporator, means to supply a power medium to the unit, fluid pressure operated piston valve means to control the supply means, means to supply fluid under pressure to the valve means operated by said variable speed unit and varying the pressure in accordance with variations in the speed of the unit, and fluid actuated means to normally permit said fluid under pressure to control the valve means.

16. In a refrigerating system having an evaporator and a variable speed power medium actuated unit to remove vapor therefrom, fluid pressure operated means to control the supply of power medium to the unit, manual means to operate the fluid pressure operated means to effect starting of the unit, means controlled by the unit to supply a fluid under a pressure varying in accordance with the speed of the unit, and a fluid pressure operated device associated with the fluid pressure operated means and the manual means to prevent operation of said unit at speeds in excess of a predetermined speed.

17. In a refrigerating system having an evaporator and a variable speed power medium actuated unit to remove vapor therefrom, fluid pressure operated means to control the supply of power medium to the unit thereby controlling the speed of the unit, manual means to operate the fluid pressure operated means to effect starting of the unit, means controlled by the unit to supply a fluid under pressure to the fluid pressure operated means and varying the pressure in accordance with variations in the speed of the unit, a fluid pressure operated device controlled by the last said means and associated with the fluid pressure operated means and the manual means to prevent operation of said unit at speeds in excess of a predetermined pressure, and means to predetermine the pressure at which said fluid operated device is actuated and to thus determine the maximum speed of the unit.
